UNITED STATES PATENT OFFICE.

HARRY A. WINTERMUTE, OF BRANCHVILLE, NEW JERSEY, ASSIGNOR TO RESEARCH CORPORATION, OF NEW YORK, N. Y., A CORPORATION OF NEW YORK.

ROTARY MEANS FOR CLEANING ELECTRODES.

Application filed April 29, 1921. Serial No. 485,521.

To all whom it may concern:

Be it known that I, HARRY A. WINTERMUTE, a citizen of the United States, residing at Branchville, in the county of Sussex and State of New Jersey, have invented certain new and useful Improvements in Rotary Means for Cleaning Electrodes, of which the following is a specification.

The present invention relates to electric precipitators such as are commonly used for separating from gas particles suspended therein.

To insure proper operation of a precipitator, the dust deposited on the electrodes must be removed from time to time and for this purpose rapping or jarring devices are usually applied.

While rapping devices such as are commonly resorted to are effective, they take up valuable space between the treater tubes and thereby lead to a reduction of the treater capacity per unit area of floor space or to a relatively large cross-section per unit capacity.

In practice the discharge electrodes must also be cleaned from time to time. It is therefore necessary as a rule, to install a separate device for cleaning the discharge electrodes in addition to mechanism for cleaning the collecting electrodes.

It is an object of this invention to provide an arrangement for cleaning electrodes which permits a close nestling of the treater tubes and thereby affords economy of flow space.

Another object is to provide a single mechanism for simultaneously cleaning both, the collecting electrodes and the discharge electrodes of the treater.

Another general object is an arrangement for the purpose indicated which is simple in construction and operation.

In its simplest aspect the invention comprises chain discharge electrodes or electrodes having the characteristics of chain electrodes and means for swinging them so that they sweep along the surface of the collecting electrodes.

To illustrate the invention reference is had to the accompanying drawings which show what I consider at present a preferred embodiment thereof.

In the drawings

Fig. 1 is an elevation; and

Fig. 2 is a plan view of an arrangement

for carrying out the objects of the invention.

The treater shown comprises four treater units, each having 16 individual tubes 10 and as many discharge electrodes 11. The electrodes which are chains are suspended from L-beams 12 resting on beams 13 of suitable construction. The treater arrangement is or may be of the usual type and need not be described in detail.

In the particular construction shown, the discharge electrodes 11 carry rapping guide frames 14, intermediate the top of the collecting electrodes and the point of suspension. These frames may be of any suitable construction. Their purpose is merely to rigidly interconnect the electrodes so as to cause them to be swung in unison when the frames are swung.

While there is considerable latitude in the selection of means for swinging the guide frames 14, I have found the arrangement shown as particularly advantageous. To the frames are connected, preferably near the center thereof, plates 15 provided with a round aperture having downwardly tapering walls.

Above the supporting frame comprising the beams 12 and 13 are mounted frames 17 and 18 for supporting shafts 19 and mechanism for raising and lowering them and for revolving them.

The shafts 19 carry at their lower ends eccentric pivots 20 fitting the apertures. When the shafts are revolved, the pivots 20 cause the frames 14 to rotate and impart a circular swinging movement to the electrodes 11.

The shafts 19 are normally, i. e., during the operation of the treater, in raised position and therefore entirely removed from the discharge electrode system. For raising and lowering the shafts 19 any suitable mechanism may be provided. In the particular construction shown I use bell crank levers 21 slidably engaging couplings 22 having the usual slide way 23 for receiving pins or journals on one arm of the levers. The levers are pivotally mounted on brackets 24. The second arm of the lever may be engaged by a rod 25, provisions being made for relative sliding movement between the arm and the rod during angular movement of the lever 21.

The shafts 19 may be driven by an electric motor 26 and bevel gears 27 and 28, the

shafts being connected to one of the gears by a sliding spline connection.

Provisions, are, of course, made for guiding the shafts in up and down direction.

5 The frames 17 and 18 may carry bearings 29 and 30 respectively in which the shafts are revolved and moved lengthwise of their axes.

The inoperative position of the shafts 19 10 is indicated in full lines in Fig. 1. When it is intended to rap the electrodes, the rods 25 are pulled outwardly, causing the bell crank levers 21 to turn to lower the shafts 19. The motor is then started to rotate the 15 frames 14.

In practice the eccentricity of the pivots 20 may be relatively small, i. e., about $\frac{3}{4}$ " in the usual treater construction. The rotation of the frames 14 will set the electrodes 20 11 in swinging condition. The centrifugal force will in practice be sufficient to carry the chains outwardly in contact with the surface of the collecting electrodes, thereby removing the deposit from them and simultaneously undergoing themselves a thorough 25 cleaning action. If the electrodes are too light to be thrown outwardly sufficiently far to carry out the cleaning function, weights may be attached thereto between the top 30 of the collecting electrodes and the guide frame 14 as indicated by the numeral 16 in Fig. 1.

It is understood that below the collecting electrodes the discharge electrodes are held 35 in centered position by the usual spacing frame (not shown). As is customary, the discharge electrodes pass through openings in the spacing frame and are normally held taut by weights.

40 While the drawings illustrate only a single form for carrying out the objects of the invention, numerous other constructions are obviously available.

The mechanism for swinging the electrodes may be applied at the bottom thereof.

I claim:

1. The combination with an electric precipitator having a flexible discharge electrode, of means for acting upon the discharge electrode to swing it into contact with the collecting electrode.

2. The combination with an electric precipitator having a flexible discharge electrode, of means for moving the discharge electrode against the collecting electrode with an impact action.

3. The combination with an electric precipitator having a flexible discharge electrode, of means for imparting circular swinging motion to the said electrode.

4. The combination with an electric precipitator having a flexible discharge electrode, of means near one end of the said electrode for imparting to it a circular swinging motion.

5. The combination with an electric precipitator having a flexible discharge electrode, of means near one end of the said electrode for imparting to it a circular swinging motion, said means including an element 70 attached to the electrode and extending transversely therefrom, a revolubly mounted shaft extending parallel to the electrode and means on the shaft for imparting a circular motion to said element. 75

6. The combination with an electric precipitator having a multiplicity of treater elements comprising each a collecting electrode and a flexible discharge electrode, of means for simultaneously acting upon the 80 discharge electrodes to swing them into impinging contact with the collecting electrodes.

7. The combination with an electric precipitator having a multiplicity of treater 85 tubes and flexible discharge electrodes therein, of means for simultaneously imparting circular swinging motion to a plurality of said electrodes.

8. The combination with an electric precipitator having a multiplicity of treater 90 tubes and flexible discharge electrodes therein, of means for simultaneously imparting circular swinging motion to a plurality of 95 said electrodes, said means including a frame interconnecting the said plurality of electrodes.

9. The combination with an electric precipitator having a multiplicity of treater 100 tubes and flexible discharge electrodes therein, of means for simultaneously imparting circular swinging motion to a plurality of 105 said electrodes, said means including a frame interconnecting the said plurality of electrodes and means for imparting circular motion to the frame.

10. The combination with an electric precipitator having a multiplicity of treater 110 tubes and flexible discharge electrodes therein, of means for simultaneously imparting circular swinging motion to a plurality of 115 said electrodes said means including a frame interconnecting the plurality of electrodes, means for imparting circular motion to the frame and means for withdrawing the last named means from the frame.

11. The combination with an electric precipitator having a multiplicity of treater 120 tubes and flexible discharge electrodes therein, of means for simultaneously imparting circular swinging motion to a plurality of 125 said electrodes, said means including a frame interconnecting the plurality of electrodes, a shaft revolubly mounted substantially parallel to the electrodes and a crank element on the shaft engaging the frame for imparting a circular motion thereto.

12. The combination with an electric precipitator having a multiplicity of treater 130 tubes and flexible discharge electrodes there-

in, of means for simultaneously imparting circular swinging motion to a plurality of said electrodes, said means including a frame interconnecting the plurality of electrodes, a shaft revolvably mounted substantially parallel to the electrodes, a crank element on the shaft engaging the frame for imparting a circular motion thereto and means for moving the shaft in axial direction away from the frame.

13. The combination with an electric precipitator having a multiplicity of treater tubes and flexible discharge electrodes there-

in, of means for simultaneously imparting circular swinging motion to a plurality of 15 said electrodes, said means including a frame interconnecting the plurality of electrodes and provided with an aperture, a shaft revolvably mounted substantially parallel to the electrodes, an eccentric on the shaft 20 engaging the aperture and means for moving the shaft in axial direction away from the frame.

In testimony whereof, I affix my signature.

HARRY A. WINTERMUTE.
